WELL PUMP

John Penrod, Okmulgee, Okla.

Application August 28, 1928, Serial No. 302,570

4 Claims. (Cl. 103—204)

This invention relates to pumps especially adapted for use in oil wells.

Briefly stated, an important object of the invention is to provide a well pump in which the working barrel thereof is reciprocated within a diametrically restricted tubing nipple to operate therewith in the formation of a lengthy choke; first to bring about a relatively rapid circulation of fluid below the outlet valve of the pump to minimize settlement of sand and second, so that when the pump is intentionally unseated for the purpose of flushing the diametrically enlarged sand receiving housing, the tubing fluid will be retarded in its descent through the housing and thereby prevented from cutting or turning the cups of the foot valve, this latter purpose of the lengthy choke being intended to provide for reseating the pump without first recapping the foot valve thereof.

A further object of the invention is to provide a well pump in which the upper traveling valve thereof is provided with a direct elevator connection permitting the pump to be started into the well without first being connected to a valve stem or the first joint of sucker rods, this feature of the invention being intended to avoid the strain incident to the connection of the pump to a valve stem or the first joint of rods while these parts are prone on a derrick floor.

The invention further contemplates a traveling valve cage in which the wings thereof are increased in cross-sectional area toward the periphery of the cage to increase the strength of the wings without impairing the fluid conducting capacity of the cage.

Another object is to provide a well pump in which the seating arrangement is such that the pump may be unseated with facility under all conditions.

Other objects and advantages will be apparent during the course of the following description.

In the accompanying drawings forming a part of the application and in which like numerals are employed to designate like parts throughout the same.

Figure 1 is a fragmentary sectional view through the pump in a seated position.

Figure 2 is a similar view through the pump in an unseated position.

Figure 3 is a vertical sectional view through the upper portion of the pump.

Figure 4 is a vertical sectional view through the lower portion of the pump.

Figure 5 is a horizontal sectional view taken on line 5—5 of Figure 3.

In the drawings wherein for the purpose of illustration is shown a preferred embodiment of the invention, the numeral 5 designates a tubing, to the lower portion of which is diametrically restricted tubing nipple 6 is connected. In other words, as shown in Figures 1 and 3, the nipple 6 has an internal diameter less than the internal diameter of the tubing 5. The lower portion of the nipple 6 has connection with a sand receiving housing 7 substantially greater in diameter than the diameter of the tubing. A foot valve shoe 8 is shown to have threaded engagement with the sand receiving housing 7 and cooperates with a foot valve 9 in forming a closure for the bottom of the housing.

The foot valve 9 is provided with a plurality of cups 10 having fluid tight contact with the wall of the longitudinal opening through the shoe 8. The ring nut 11 on the lower portion of the foot valve rests upon an internal annular shoulder 12, of the foot valve shoe.

The foot valve 9 is shown to be connected to the lower portion of a tubular anchor 14 and the tubular anchor is in turn suspended from and is in open communication with the tubular body 16 of the piston.

It will be seen that the piston is relatively fixed and is provided with a plurality of downwardly presented cups 18 having fluid tight contact with the wall of a movable working barrel 19. The upper portion of the relatively fixed piston is provided with what might be said to be a standing valve 20 having a ball which is unseated during the upstroke of the working barrel and is unseated during the downstroke of the barrel.

The lower portion of the working barrel 19 carries a bushing 21 encircling the piston body 16 and adapted for striking engagement with the nut 22 to unseat the pump. Of course, the bushing 21 is engaged with the nut 22 only when it is desired to unseat the pump for the purpose of flushing, the special sand receiving housing 7 or for removing the equipment to the surface.

Figures 1 and 2 illustrate that an upper traveling valve cage 32 is connected to the upper portion of the working barrel 19 through the medium of a cage nut 28 and that the cage is provided with a shank having an abruptly reduced or shouldered portion 30 defining an elevator connection which enables the pump to be started into the well before being connected to a valve stem or the first joint of rods. In other words, previous to the introduction of the pump into a well an elevator of conventional or other design is connected directly to the abruptly reduced portion 110

30 so that the pump may be raised from a horizontal position on the derrick floor to a vertical position immediately above the well into which the pump is to be lowered. The lifting effort is applied directly to the pump without the intervention of a valve stem and consequently bending of the valve stem preparatory to the introduction of the pump into the well is avoided.

After the pump is started into the well a valve stem or the first joint of rods is connected to the valve cage with the aid of manually operated wrenches. Since this connection is made while the parts are positioned vertically the attendants are less likely to use destructive force. In this connection it might be pointed out that a pump is ordinarily connected to the first joint of rods or to the valve stem while these parts are positioned horizontally on a derrick floor and the ease with which the wrenches may be handled increases the possibility of making this joint unnecessarily tight and consequently weakening the same. Also, the unnecessary force often used in connecting the upper traveling valve cage to the first joint of rods or to a valve stem weakens the wings of the cage so that after a short period of use the valve cage is broken and the pump must be fished out of the well.

It will be seen that the shank of the upper traveling valve is provided at a point above the elevator connection 30 with flats for engagement by the jaws of a wrench. By this arrangement the strain incident to the connection of the valve cage to the valve stem or the first joint of rods is not borne by or transmitted through the elevator connection or the wings of the cage. Therefore, the wings of the upper cage are required only to resist the longitudinal strain incident to the work stroke of the pump. In this manner, the possibility of broken cages is reduced to a minimum.

It is admirably illustrated in Figure 5 that the wings of the upper traveling valve cage 32 are increased in cross-sectional area toward the periphery of the cage so that the side walls of each opening in the cage occupy substantially parallel planes. By this arrangement the strength of the cage is tremendously increased without the slightest impairment to the fluid conducting capacity of the cage.

The lower portions of the wings of the upper traveling valve have the inner surfaces thereof offset inwardly to guide the ball valve 33 axially to its seat. This assures prompt seating of the ball valve and at the same time greatly increases the period of usefulness of the ball and seat. When the ball valve is unseated the space between the same and the wings will be greatly increased and thoroughly scavenged of sand which might subsequently interfere with the seating of the ball.

The shank of the upper traveling valve cage may be provided with either a pin or box by which the pump may be connected to the sucker rods without the intervention of a valve stem.

In operation, the working barrel is reciprocated to bring about the alternate filling and emptying of the pump chamber which, as is clearly shown in the drawings, extends from the standing valve 20 to the upper traveling valve 26.

It is shown in Figures 1 and 2 that the working barrel has a very limited clearance within the diametrically restricted tubing nipple to cooperate therewith in the formation of a lengthy choke by which a relatively rapid circulation of fluid is maintained in that portion of the tubing

nipple below the upper traveling valve so that the settlement of sand in the special sand receiving housing is minimized. In explaining this, it is pointed out that the tubing nipple fluid displaced on the downstroke of the working barrel 80 will be moved up through the limited choke or passage defined by the barrel and tubing nipple and will thereby hold the sand in suspension.

On the upstroke of the pump, the fluid seeking to take the place of the space vacated by the ascending barrel will be retarded by the limited space between the barrel and nipple so that the sand is not only held in suspension, but the pressure at the lower end of the barrel is substantially reduced to relieve the cups 18.

From time to time, depending upon the volume of sand which settles into the housing 7, the pump may be unseated to allow the tubing fluid, or a portion of it, to flush down through the housing to return the accumulated sand to the well. It is important to observe that the lengthy choke defined by the working barrel 19 and the tubing nipple not only performs the functions outlined in the immediately preceding paragraph but it throttles the descent of the tubing fluid used for flushing purposes so that the movement of this fluid through the diametrically enlarged housing is relatively slow. In explaining this, attention is invited to Figure 2, in which it is illustrated that the annular sand receiving chamber between the anchoring member 14 and the surrounding housing 7 is vastly superior in cross-sectional area to the cross-sectional area of the restricted fluid passage 95 between the working barrel and the diametrically restricted nipple 6, so that when the pump is unseated the descent of tubing fluid through the housing will be extremely slow as compared to the rate of descent of fluid through the restricted entrance opening to the housing and such slow

descent of fluid prevents the destructible cups 10 from being turned outward with the result that the proper re-seating of the pump is assured. Therefore, during the flushing operation the descending fluid is prevented from engaging the 115 cups 10 of the foot valve with sufficient force to turn and consequently destroy the same. Thus, the pump may be reseated without recapping the foot valve. In other words, the relative diameters of the opposed walls of the barrel 19 and 120 the surrounding tubular member 6 constitutes a definite means embodying an annular chamber or passage of restricted cross-sectional area, by which, during the operation of the pump in the recovery of fluid, the fluid in said passage is 125 caused to travel at a much higher rate than the tubing fluid above and by which the descent of tubing fluid through the sand housing is retarded when the cup is unseated for flushing purposes.

The substantial space between the tubular anchor and the sand housing will prevent the sand deposited therein from freezing the tubular anchor in seated position. That is to say, the cross-sectional area of the wall of accumulated sand 130 surrounding the tubular anchor will be such that the sand cannot effectively bind the anchor in place.

Having thus described the invention, what is claimed is:

1. In a pump, a tubular member, a sand receiving housing below said tubular member and being of a substantially greater diameter than the same, a movable working barrel in said tubular member and having a limited clearance from the 150

wall thereof and cooperating therewith in defining an elongated diametrically restricted entrance opening to said housing of substantially greater diameter to retard the descent of fluid through the housing, an outlet valve at the upper portion of said working barrel, the movement of said working barrel creating a relatively rapid fluid movement in said elongated restricted entrance opening at a point below said valve, and a piston 10 in said working barrel and having an anchor member provided with cups movable into said housing and the path of the retarded descent of fluid through the housing.

2. In a structure of the character described, a tubular member, a housing below the tubular member and being of a greater diameter than the same, a pumping unit within said tubular member and being provided with a foot valve having cups, a foot valve shoe engaged by said cups, said pumping unit having a limited clearance in said tubular member and cooperating therewith in throttling the descent of fluid and thereby protecting said cups when the pumping unit and the foot valve thereof are unseated and the foot valve and the cups thereof positioned in said housing of greater diameter.

3. In a fluid lift, a tubing, an elongated nipple attached to the tubing and having a diameter less than the diameter of the tubing, a sand housing suspended from said nipple and having a seat, and a pumping unit extending through said hous-

ing and having a foot valve to engage said seat and thereby close the lower portion of said sand housing, said pumping unit having an elongated pumping element movable through said nipple in slightly spaced relation to the wall thereof to cooperate therewith in the formation of a lengthy diametrically restricted passage between the tubing and said housing to throttle the descent of fluid through the housing when said foot valve is unseated and positioned in said housing and causing the accelerated flow of fluid in the region of the elongated element of the pumping unit when the pump is operated.

4. In a fluid lift, a tubing, an elongated nipple attached to the tubing and having a diameter less than the internal diameter of the tubing, a sand housing below said nipple and having a seat, and a pumping unit extending through said housing and having a member extending through said housing and having a foot valve to engage said seat, the upper portion of said pumping unit having an outlet and provided below said outlet with an elongated element movable through said nipple in slightly spaced relation to the wall thereof to cooperate therewith in the formation of a diametrically restricted passage between the tubing and said housing to accelerate the flow of fluid below said outlet when the pump is operated and to throttle the descent of fluid when said foot valve is unseated and positioned in said housing.
